SPECTACLE FRONT

Austin B. Belgard, Evanston, Ill.

Application September 15, 1951, Serial No. 16,665

Term of patent 7 years

(Cl. D57—1)

To all whom it may concern:

Be it known that I, Austin B. Belgard, a citizen of the United States, residing at Evanston, county of Cook, and State of Illinois, have invented a new, original, and ornamental Design for a Spectacle Front, of which the following is a specification, reference being had to the accompanying drawing, forming a part thereof, in which:

Figure 1 is a front view in elevation of a spectacle front showing my new design; Fig. 2, a top plan view; Fig. 3, an end view; Fig. 4, an end view of the end opposite to that shown in Fig. 3; and Fig. 5, a rear elevational view.

I claim:

The ornamental design for a spectacle front, as shown.

AUSTIN B. BELGARD.
